UNITED STATES PATENT OFFICE.

JULIUS SCHWARZ, OF UNION HILL, NEW JERSEY, ASSIGNOR OF ONE-THIRD TO SAID JULIUS SCHWARZ, ONE-THIRD TO EDWARD NUFER, AND ONE-THIRD TO ABE BACHARACH, ALL OF UNION HILL, NEW JERSEY.

EMBROIDERED FABRIC.

1,149,956.

Specification of Letters Patent. Patented Aug. 10, 1915.

Application filed February 18, 1914. Serial No. 319,388.

To all whom it may concern:

Be it known that I, JULIUS SCHWARZ, a citizen of the United States, and a resident of Union Hill, in the county of Hudson and State of New Jersey, have invented a new and Improved Embroidered Fabric, of which the following is a full, clear, and exact description.

The invention relates to embroidery and its object is to provide a new and improved 10 embroidered fabric such as is used for flounces and the like on women's dresses and other garments, the embroidered fabric being provided with an embroidered border arranged to allow the lower portion of the 15 fabric to overlie a portion of the border without being attached thereto, with a view to produce a very fine effect.

In order to accomplish the desired result, 20 use is made of the main body of a fabric material provided with embroidery ornaments, and a border of a woven fabric material provided with embroidery ornaments and partly underlying the said main body, 25 sundry of the stitches of the said embroidery ornaments on the main body engaging the said border to fasten the latter in position on the main body a distance from the edge of the latter.

30 A practical embodiment of the invention is represented in the accompanying drawings forming a part of this specification, in which similar characters of reference indicate corresponding parts in all the views.

35 Figure 1 is a front elevation of the embroidered fabric; Fig. 2 is a rear face view of the same; and Fig. 3 is an enlarged cross section of the same on the line 3-3 of Fig. 1.

40 The main body A is preferably made of closely-woven fabric material and is provided with embroidery ornaments B produced in the usual manner on a suitable embroidery machine by forming stitches according to a predetermined design. A border C, preferably of net or open mesh fabric, has its upper portion underlying the body A while the lower portion of the border depends from the lower edge of the 45 body A, and this lower portion is provided with embroidery ornaments D produced on the embroidery machine by stitches, the same as the ornaments B. The border C is attached to the body A by sundry of the

stitches forming the ornaments B, but in 55 such a manner that the lower portion of the body A freely overlies the border C without being attached thereto. Thus, as shown in the drawings, the stitches used for fastening the border C to the body A are located 60 above the line E, E indicated in the drawings, and consequently the portion of the body A below this line E overlies the border C without being attached thereto, as will be readily understood by reference to 65 Fig. 3.

By reference to Fig. 2, it will be noticed that the stitches used for fastening the border C in place on the body A appear raised on the back of the border, while the stitches 70 of the ornaments B below the line E, E do not appear on the back of the border.

The edges of the body A and border C are preferably scalloped and embroidered 75 to give a fine finish to the fabric.

By reference to Fig. 2, it will be noticed that the upper edge of the border C practically overlies the embroidery ornaments B, and the upper portion of the border C is not visible from the front of the fabric 80 except at those ornaments B which are cut out, as indicated in Fig. 1. Thus a very desirable effect is obtained especially as the lower portion of the body A overlies the border C without being attached thereto, 85 thus rendering the fabric soft and pliable and allowing movement of the lower part of the border C and the lower portion of the fabric A when the fabric is used on a dress or other garment.

Having thus described my invention, I claim as new and desire to secure by Letters Patent:

1. An embroidered fabric, comprising a main body of a closely woven fabric material provided with embroidery ornaments, and a border of an open mesh fabric material having its upper portion underlying the said main body and having its lower portion depending from the main body and provided with embroidery ornaments, sundry of the stitches of the said embroidery ornaments of the main body engaging the said border at points a distance above the lower edge of the main body to fasten the border 100 to the main body, the lower portion of the main body being disconnected from the border. 105

2. An embroidery fabric, comprising a piece of closely woven fabric having embroidery ornaments thereon sundry of which are cut out, and a piece of open mesh fabric secured to the rear of the first piece under the embroidery ornaments thereof and extending below and depending from the lower edge of the said first piece, the depending portion of the second piece of fabric being provided with embroidery ornaments.
3. An embroidery fabric, comprising a piece of closely woven fabric provided with embroidery ornaments, sundry of which are cut out and having a scalloped and embroidered edge, and a second piece of open

mesh fabric at the rear of the first piece and secured thereto by sundry of the stitches of the said ornaments, with its lower portion extending below the lower edge of the first piece, the said lower portion of the open mesh fabric being free and provided with embroidery ornaments and scalloped and embroidered edge.

In testimony whereof I have signed my name to this specification in the presence of two subscribing witnesses.

JULIUS SCHWARZ.
